FIG. 6

UNITED STATES PATENT OFFICE.

EUGENE PARKER, OF LOS ANGELES, CALIFORNIA.

TITLE.

Application filed February 9, 1927. Serial No. 166,855.

This invention relates to improvements in tiles, facing tiles and the like, especially used for floors, walls, and mantelpiece work, or similar constructions, and has for one of its principal objects the provision of a tile which will automatically be spaced from other tiles in the laying process.

One of the important objects of this invention is to provide in a tile, a plurality of integral projections, which, when the same is placed in conjunction with other tiles, or similar objects, will be automatically spaced from such other tiles for purposes of cementing into proper position and affording a more uniform and neat appearing joint.

Still another and further important object of this invention is to provide in a tile a plurality of combined spacing and interlocking elements integral with the tile itself whereby more uniform and solid constructions will result when said tiles are laid in a floor or in any similar structure.

Other and further important objects of this invention will be apparent from the disclosures in the accompanying drawings and following specification.

The invention, in a preferred form, is illustrated in the drawings and hereinafter more fully described.

30 In the drawings:

Figure 1 is a top plan view of an improved tile, constructed according to this invention.

Figure 2 is a similar view illustrating a slight modification of the invention.

Figure 3 is a top plan view of a hexagonal tile constructed in accordance with a still further modification of this invention.

Figure 4 is a detail view, parts being broken away, of a pair of tiles spaced apart and also interlocked by the improved means of this invention.

Figure 5 is a view similar to Figure 4, illustrating another modification of the invention.

Figure 6 is a side elevation of two tiles joined in accordance with this invention.

Figure 7 is a longitudinal vertical section of the tiles shown in Figure 6.

As shown in the drawings:

50 The reference numeral 10 indicates generally a tile, which may be of clay, porcelain, wood, cork, rubber, cement composition, or of any other similar or suitable material, and which, as shown in this figure, is square.

55 However it is obvious that the tiles may be

varied through quite a wide variety of shapes, sizes, and figures without varying from the principles laid down in this invention.

Along each edge of the tile 10 extends a slight projection as shown at 12 of Figure 1, and which is integral with the tile material but does not, in the usual preferred construction, extend completely up the side of the tile but only approximately one-half the height thereof.

In Figure 2 is shown a slight modification of this construction, wherein a tile 14 is provided along its edges with projections 16, preferably two along each side of the tile, and which when laid against similar tiles results in a uniform construction which will automatically space such tiles in proper juxtaposition to each other and at the same time allowing the cement in which the tiles are laid to entirely surround and grip the edges of said tiles.

In Figure 3 is shown a hexagonal tile 18 having a plurality of projections, in this case shown as three in number, along each edge thereof. These projections accomplish the same purpose as the projections 12 and 16 of the tiles 10 and 14 as shown in Figures 1 and 2, respectively.

In Figure 4 is shown a slight adaptation of the invention wherein one tile 22, having a plurality of lugs, preferably two in number, along each edge thereof, as shown in 24; co-operates with a tile 26 having a single lug 28 on each side or edge thereof, this lug 28 fitting in between the lugs 24 of the corresponding or juxtaposed tile 22.

In the modification shown in Figure 5, each of the tiles may be provided along at least two edges thereof with two or more lugs or projections 32, one preferably positioned at or near each corner, so that when the tiles 30 are set in position, as illustrated in this figure, the lugs 32 act both as interlocking elements and also as spacing elements whereby the correct distances between the tiles 30, along at least longitudinal lines, is maintained.

Obviously other integral lug formations, such as those shown at 12 and 16, may be used along the other edges of the tiles 30, or the construction shown at 24 and 28 may also be employed in combination with the other forms of this invention.

Any combinations of the integral lugs may

be used along the edges of any certain tile as desired or convenient, and it will be seen that herein is provided automatically operating means and methods of spacing tiles correct distances apart when the same are laid, thereby insuring a more uniform construction and at the same time these spacing lugs may be employed to act as interlocking members, whereby the tiles themselves may be more 10 securely fixed in position with respect to each other. These lugs themselves may extend upwardly throughout the thickness of the tile if desired or may include merely any desired portion of the thickness. Further, the lugs 15 may be spaced higher on one tile than on the next adjacent tile, thereby providing a very desirable locking feature, which also operates as a spacing element. It will be noted that when the lugs are used as locking means 20 in addition to spacing means they are prefer-

ably of approximately twice the depth of the lugs which are used simply as spacing elements.

I am aware that many changes may be made and numerous details of construction varied throughout a wide range without departing from the principles of this invention and I, therefore, do not purpose limiting the patent granted hereon otherwise than as necessitated by the prior art.

I claim as my invention:

As a new article of manufacture, an hexagonal tile having integral interfitting and spacing lugs along the edges thereof, said interfitting lugs being spaced alternately for juxtaposed tiles, the said interfitting lugs also adapted to be completely surrounded by mortar when the tiles are laid.

In testimony whereof I affix my signature.

EUGENE PARKER.
